John Steeward,
ATTORNEY.

UNITED STATES PATENT OFFICE.

WILLIAM STEVENSON, OF MORRISTOWN, NEW JERSEY.

MEANS FOR PROTECTING VESSELS AGAINST TORPEDO ATTACKS.

1,282,486.

Specification of Letters Patent. Patented Oct. 22, 1918.

Application filed November 21, 1917. Serial No. 203,130.

To all whom it may concern:

Be it known that I, WILLIAM STEVENSON, a citizen of the United States, residing at Morristown, in the county of Morris and

5 State of New Jersey, have invented certain new and useful Improvements in Means for Protecting Vessels Against Torpedo Attacks, of which the following is a specification.

10 My object in this invention is to provide means for protecting vessels against torpedo attack so constructed that when not in use it may be readily drawn up out of the water, so as not to impede the progress of 15 the vessel, and when in use it will receive the impact of the torpedo with the minimum of possibility of causing explosion thereof, and, if explosion does occur, without injury being imparted to the vessel. To these ends I employ 20 a net or net-like element held stretched in a surrounding frame, and to prevent the torpedo from penetrating the same I provide for cushioning the frame with springs which will yield and so absorb the shock of 25 impact. These springs are supported by another frame or equivalent which is in turn supported by suitable arms attached (preferably pivotally) to the vessel's side, and these arms may be telescopic and they 30 have cushion springs resisting the movement of the second frame inward and serving, in case the war-head of the torpedo should operate or the torpedo should otherwise be caused to explode, to absorb the shock of the 35 explosion so that the vessel would not be injured by the resultant force transmitted through one or more of the arms. My invention therefore contemplates stopping the torpedo without exploding it, if possible; 40 and then, if explosion perchance does occur, causing the incidental shock to be absorbed before it can be transmitted to the vessel's hull.

In the accompanying drawing,

45 Figure 1 is a side elevation of a vessel provided with the improved means;

Fig. 2 shows the vessel in section, the said means being in operative position to resist torpedo attack;

50 Fig. 3 is an inside elevation of the structure *a*—*c* to be described in detail;

Fig. 4 is an enlarged fragmentary sectional view of the two frames and the interposed cushioning means; and

55 Fig. 5 shows one of the telescopic arms and its cushioning means.

The improved means is arranged along each side of the vessel so as to protect vital parts, or, if desired, the whole length of the vessel as is shown in Fig. 1. Usually it will 60 be constructed in sections, especially when any considerable part of the length of the ship is to be protected, all the several sections being substantially alike. A description of any one section will serve for any 65 of the others.

a is a rectangular frame in which is suitably stretched and secured a net *b* strong enough, when the frame is supported against movement out of its own plane by yielding 70 springs as will be explained, to resist puncture or rupture by a torpedo, or it may be a mine. Parallel with and opposite this frame and conforming in shape and size thereto is a rectangular frame *c*. Each frame has projecting from it and secured to it a set of rigid studs, bolts or equivalent *d*, the bolts of one frame penetrating and sliding freely in the other, the separating movement of the two frames being limited by suitable stops 75 *e* on the studs. Preferably the studs on one frame alternate with those on the other. Coiled about each stud and interposed between the frames is a spiral spring *f*, the several springs maintaining the frames 80 apart a distance determined by the stops *e*. It will be noted that the several studs serve to support the frame *a*, frame *c* being supported in the manner now to be explained.

At the four corners of the frame *c* and 90 on its inner face are provided hinging lugs *g*. In corresponding arrangement there are provided on the side of the vessel *h* a set of four hinging brackets *i*, each of which affords at *j* a stop. Connecting each lug on the frame *c* with the corresponding bracket *i* on the side of the vessel is an arm denoted generally in Fig. 2 by the character *k*. Referring to Fig. 5, this arm includes two telescopic members *l* and *m*, the tubular 100 member of which has a slot *n* to receive a pin *o* on member *m* and limit the telescoping movement of said members; the members are provided with fixed collars *p* between which is interposed, coiled around said members, a spiral spring *q*, which normally holds the arm extended to the limit afforded by the slot *n* and pin *o*, or substantially so. The outer end of member *m* is pivoted to a lug *g* on frame *c* by a bolt *r* (Figs. 2 and 3); 105 the inner end of member *l* is pivoted to a bracket *i* by a bolt *s*, and it has a stop *t* 110

which, when the arm is in the position shown in Fig. 2 abuts the stop *j* and holds the arm substantially horizontally.

The structure including the connected frames *a*—*c* and the four arms *k* may be raised and lowered, parallel-lever fashion, by any suitable means, for instance, the winch *u* shown in Fig. 2 and cables *v* extending over pulleys *w* and attached at their ends to suitable parts of the apparatus. Thus, when the device is in use, it will stand more or less submerged, as shown in Fig. 2; when it is not in use, it may be swung up against the vessel's side, so as not to impede her progress through the water.

When the device is in use, if a torpedo or mine strikes the shield afforded by the net *b* and its frame the springs *f* will yield, thus if possible to avoid exploding the charge. Should, however, an explosion occur, the shock thereof would be absorbed by the springs *f* and the springs *g*, and therefore not be transmitted through the arms *k* with sufficient force to injure the vessel's side. To this end it will be understood that the springs *f* impose very considerably less resistance than the springs *g*.

If desired, the inner frame *c* may also be provided with a net *x* (Fig. 4) so that should the torpedo or other obstacle pene-

trate the net *b* it will be checked by the net *x*.

Having thus fully described my invention, what I claim as new and desire to secure by Letters Patent, is:

35

In combination, with a vessel, an open frame arranged outwardly thereof in an upright plane and spaced from the vessel, a net stretched in the frame, supporting means for the frame attached to the vessel and including another open frame conforming in shape and size to and arranged opposite and spaced from and inwardly of the first frame, a set of studs projecting horizontally from one frame and penetrating and arranged to 40 slide freely in the other frame, and upper and lower pairs of spaced telescopic arms each pivoted to the vessel at one end and to the second-named frame at the other, the pivots between each arm and the vessel and 45 said second frame being horizontal, a spring on each arm interposed between the telescoped members thereof and resisting inward yielding of the outer arm member, and other springs interposed between said frames 50 and resisting inward yielding of the first or outer frame, the latter springs offering less resistance than the first springs.

In testimony whereof I affix my signature,

WILLIAM STEVENSON.
